UNITED STATES PATENT OFFICE.

CHARLES W. SLEEPER, OF LANCASTER, NEW HAMPSHIRE, ASSIGNOR TO
THE SLEEPER MACHINE COMPANY, OF MAINE.

CAN-NUMBERING MACHINE.

SPECIFICATION forming part of Letters Patent No. 663,048, dated December 4, 1900.

Application filed August 23, 1900. Serial No. 27,808. (No model.)

To all whom it may concern:

Be it known that I, CHARLES W. SLEEPER, a subject of the Queen of Great Britain and Ireland, residing at Lancaster, in the county 5 of Coos and State of New Hampshire, have invented a new and useful Can-Numbering Machine, of which the following is a specification.

In the process of putting up food products 10 in tin cans it is frequently desirable to provide for the identification of each can and the process through which its contents have passed. For this purpose each "batch" of goods is given a serial number, which is 15 stamped upon each can of the batch, and a record of the process is filed under the same number.

The object of my invention is to provide 20 convenient means for numbering the cans and incidentally for inspecting the cans before numbering.

In the drawings accompanying this specification, Figure 1 is an end view of my invention with stamps resting upon the cans. Fig. 25 2 is a top view of Fig. 1. Fig. 3 is an end view with stamps resting upon the ink-pad. Fig. 4 is a top view of Fig. 3. Fig. 5 is a detail showing the action of the turnstile-latch.

A is a conveyer-trough.

30 A² is an endless belt resting upon the bottom of the trough and having continuous motion in the direction of the arrows.

a a' are brackets secured to the under side of the trough A.

35 a² is a hanger adjustably secured to the bracket a.

a³ is a hanger adjustably secured to the bracket a'.

40 a⁴ is a gear rigidly secured to the hanger a'. b is a shaft journaled in the hangers a² a³ and provided with projecting arms b' b', terminating in the handles b² b³.

b³ is a gear pivoted upon a pin projecting from the side of the arm b'.

45 b⁴ is a gear secured to a shaft b⁵, which is journaled in the arms b' b'.

b⁶ b⁶ b⁶ are blocks adjustably secured upon the shaft a⁵ and carrying suitable type-holders b⁷ for holding a number of figures of rubber type t.

b⁸ is a trough which carries an ink-pad b⁹ and is secured to the hangers a² a³.

In Figs. 3 and 4 the rubber type are resting upon the ink-pad b⁹. In Figs. 1 and 2 the handles b² have been moved through an 55 arc of about one hundred and eighty degrees, and the rubber type rest upon the tops of the cans C C. The gears a⁴ b⁴ being of equal diameter, the type-holders maintain a vertical position during the movement of the handles b².

c is a turnstile revolving upon a vertical pin projecting from the bracket a'. One arm of the turnstile is provided with an upwardly-projecting lug c'.

65 c² is a latch-bolt provided with two downwardly-projecting lugs c³ c⁴, adapted to engage alternately the lug c' on the turnstile c in the manner hereinafter described, the said lugs c³ c⁴ being a short distance apart and the lug c⁴ 70 being situated a little in advance of the other in the direction of the movement of the turnstile.

c⁵ is a lever pivoted on a pin upon the side of hanger a³ and attached to the latch-bolt c². 75 A spring c⁶ connects the lever c⁵ with the upper end of hanger a³. A pin c⁷ upon the arm b' engages the lever c⁵ and throws it back, as shown in Fig. 3.

In operation, the device being in the position shown in Figs. 3 and 4, the lug c' engaging the lug c³, the cans C C moving along the conveyer are stopped by the turnstile and the operator inspects them and removes any defective cans. When six cans have passed 80 inspection, the operator takes hold of the handles b² b³ and moves them to position shown in Figs. 1 and 2, stamping the numbers upon the cans. As the handles begin to move, the spring c⁶ pulls the lever c⁵ forward and throws the latch c², relieving the lug c' from engagement with the lug c³, allowing the turnstile to move a short distance until the lug c' engages the lug c⁴. This slight movement takes no appreciable time, and the cans are at rest 95 before the rubber type strike them. The handles b² b³ are immediately thrown back to their first position, by which movement the pin c⁷ acts upon the lever c⁵ to throw the latch c² in the opposite direction, releasing 100

the lug c' and allowing the turnstile to revolve until the lug c' again strikes the lug c^3 , during which time six cans will have passed the turnstile.

5 The device may of course be constructed to handle cans in sets of any convenient number; but the cans being usually handled in dozens, six cans is found to be a convenient number for a set.

10 What I claim, and desire to secure by Letters Patent, is—

1. In a can-numbering machine the oscillating arms b' carrying the cross-shaft b^5 , type-blocks b^6 mounted on said cross-shaft ink-pad b^9 , means for feeding the cans and retaining them in position to be acted upon by the printing mechanism, and means for removing the numbered cans substantially as described.

20 2. In a can-numbering machine the conveyer-trough A with endless belt A^2 adapted to move continuously therein, oscillating arms b' with type-carrying mechanism mounted thereon, turnstile c and means for alter-

25 nately locking and unlocking said turnstile at each oscillation of said arms b' substantially as described.

3. In a can-numbering machine the con-

veyer-trough A with endless belt A^2 adapted to move continuously therein, oscillating arms b' with type-carrying mechanism mounted thereon, turnstile c provided with lugs c' , latch-bolt c^2 provided with lugs $c^3 c^4$ and means for giving said latch-bolt reciprocating motion at each oscillation of said arms b' substantially as described.

4. The can-numbering device above described consisting of the conveyer-trough A, with endless belt A^2 adapted to move continuously therein, oscillating arms b' , carrying the shaft b^5 with the type-blocks b^6 mounted thereon, gears $a^4 b^8 b^4$ for preserving the upright position of said type-blocks during the oscillation of said arms b' , ink-pad b^9 , turnstile c provided with the lug c' , latch-bolt c^2 provided with the lugs $c^3 c^4$, oscillating lever c^5 pivoted to said latch-bolt and operated by the arms b' and spring c^6 substantially as described.

In testimony whereof I have signed my name to this specification in the presence of two subscribing witnesses.

CHARLES W. SLEEPER.
